CLAIM

The ornamental design for an advertising receptacle, as shown and described.

DESCRIPTION

FIG. 1 is a perspective view of the advertising receptacle of the present invention with a first top section;

FIG. 2 is a first side view of the advertising receptacle of FIG. 1;

FIG. 3 is a second side view of the advertising receptacle of FIG. 1;

FIG. 4 is a third side view of the advertising receptacle of FIG. 1;

FIG. 5 is a fourth side view of the advertising receptacle of FIG. 1;

FIG. 6 is a top view of the advertising receptacle of FIG. 1;

FIG. 7 is a bottom view of the advertising receptacle of FIG. 1;

FIG. 8 is a perspective view of the advertising receptacle of FIG. 1 with a second top section;

FIG. 9 is a perspective view of the advertising receptacle of FIG. 1 with a third top section;

FIG. 10 is a perspective view of the advertising receptacle of FIG. 1 with a fourth top section;

FIG. 11 is a perspective view of the advertising trashcan of FIG. 1 with a fifth top section; and,

FIG. 12 is a perspective view of the advertising receptacle of FIG. 1 with a sixth top section.

The broken lines showing additional features of the advertising receptacle are for illustrative purposes only and form no part of the claimed design.
